UNITED STATES PATENT OFFICE.

CHARLES L. MOHR, OF CHICAGO, ILLINOIS, ASSIGNOR TO MOHR LINO-SAW COMPANY, OF CHICAGO, ILLINOIS, A CORPORATION OF ILLINOIS.

GUIDE FOR LINOTYPE-MACHINES.

1,358,972.

Specification of Letters Patent. Patented Nov. 16, 1920.

Application filed February 4, 1918. Serial No. 215,290.

To all whom it may concern:

Be it known that I, CHARLES L. MOHR, a citizen of the United States, and resident of Chicago, county of Cook, and State of Illinois, have invented a certain new, useful, and Improved Guide for Linotype-Machines.

My invention relates to improvements in type-bar casting machines and has special reference to an improved guide for use on 10 linotype machines for controlling the movement of linotype slugs.

The object of my invention is to provide a device for guiding the slugs or type-bars as they fall down the chute upon the "stick" 15 or assembly platform, which shall be capable of being quickly and readily adjusted to guide long or short slugs; which shall be simple in construction; which shall always be in position for use; and which shall be 20 readily extensible and retractable as to length.

My invention consists in an inclined stick or assembly platform adapted to receive slugs of different lengths at its upper edge 25 and down which the slugs are adapted to slide, in combination with a wall or guide which is adjustable as to length so that either short or long slugs may be properly guided as they descend the stick, to the end 30 that when long slugs are produced the wall or guide may be retracted so as to not interfere with the proper assembling of the slugs upon the platform.

My invention also consists in the several 35 features of construction and in the arrangements and combinations of parts whereby I am enabled to attain the above mentioned and other objects and all as hereinafter described and particularly pointed out in the 40 appended claims.

My invention will be more readily understood by reference to the accompanying drawings forming a part of this specification, and in which:—

45 Figure 1 is a fragmentary side elevation, partly in section, of the front part of the slug making mechanism of a linotype machine;

Fig. 2 is a fragmentary front elevation of 50 the portion of a linotype machine shown in Fig. 1;

Fig. 3 is an enlarged fragmentary vertical section on the line 3—3 of Fig. 2; and

Fig. 4 is a substantially horizontal section 55 on the line 4—4 of Fig. 3.

This present invention is particularly related to and useful in conjunction with my invention of a type-bar sawing device as disclosed in my co-pending application Number 825,049, filed March 16, 1914, for 60 patent on "linotype machines." The device of the former application was especially adapted for producing linotype slugs or type-bars of different or varying lengths from a fraction of an inch to five inches or 65 more, and in the use of said device upon linotype machines of standard make, I have found a difficulty in properly assembling the different lengths of slugs upon the stick or assembly platform of the machine. My 70 present invention has for its object the overcoming of this difficulty.

In the said drawings 1 illustrates generally the forward part of the slug producing mechanism of a linotype machine as 75 provided with my slug sawing mechanism illustrated and described in my said co-pending application.

Linotype machines are usually provided with a mold wheel 2 provided with mold 80 slots 3 in which slugs 4 of substantially five inches in length are cast. The machine also has a reciprocating slug ejector 5 which is adapted to force the slug 4 out of the mold 3 when the same is in a vertical position, as 85 shown in the drawings. As the slug is pushed out of the mold 4 by the ejector 5, it passes through a trimming mechanism 6 by which it is sized as to thickness, and in front of this trimming mechanism I have arranged 90 a slug cutting saw 7 in a casing 8.

The saw is carried by a shaft 9 and is movable up and down in front of the mold slot by the mechanism fully described in my 95 said co-pending application. The saw 8 is thus arranged for the purpose of cutting the slugs as they are ejected from the machine into an upper and a lower part. The upper part is waste and passes out of the machine down a waste chute, not shown, and the 100 lower part carries printing characters and is the article which it is desired to produce upon the machine. This lower or printing part 10 of the slug, as soon as it is severed from the upper part, drops vertically down 105 the narrow vertical chute 11 upon a curved guide plate 12 by which it is turned with its forward or printing face uppermost, and it then slides down upon the downwardly inclined stick or assembly platform 13. As 110

2

shown in the several figures, the stick is wide enough from its lower edge 14 to its upper edge 15 to receive the longest slugs, and, as illustrated in Fig. 2, all of the slugs, 5 of whatever lengths, slide down upon this platform until their lower ends rest against the rib or ridge 14 at the lower edge of the stick. To close one side of the chute 11 and thus form the narrow vertical chute down 10 which the slugs drop, I provide the thin plate 17 which I extend at its lower end down over the upper part of the stick 13. At the lower part of the stick and in substantial alinement with the plate 17 is a 15 pusher 18. This pusher is mounted for movement longitudinally of the stick 13 and immediately above same and is adapted to automatically push the slugs along on the stick one after the other after they have 20 reached the lower edge of the stick. This pusher is a part of the usual linotype machine and does not need to be particularly described as to its operation, except to say that as a slug slides down it draws back into 25 alinement with the plate 17 and out of the path of the descending slug, and then immediately moves forward and pushes the slug along the stick out of the path of the next descending slug.

30 As best shown in Fig. 2, the forward face 19 of the pusher, together with the plate 17, forms one wall of the slot down which the slugs fall, and my invention relates particularly to an extensible and retractable guide 35 which is adapted to form the opposite wall of the said chute or slot.

For this purpose I provide a jointed guide 40 formed of a series of short thin strips or bars 21 pivotally joined end to end and capable of being folded back upon themselves, as shown in full line in Fig. 2, or extended in end to end relation, as shown in dotted lines in said figure. I pivotally mount this jointed guide at one end to the linotype machine 45 at one side of the chute 11 near the lower end thereof or where the slugs strike the curved plate or guide 12. The guide 20 is set on edge and is capable of being extended or lengthened in position opposite to the 50 lower end of said plate 17 and the inner face 19 of the pusher 18 so as to form the opposite wall of the chute down which the slugs move on the stick 14. I make the guide 20 yieldable laterally so that even should a slug 55 be caught between the end of the pusher and the guide no damage can result.

It will now be clear that I am enabled to guide the extremely short slugs as well as the longer ones, and when I change the machine from producing short slugs to produc-

ing longer ones, I can readily shorten the guide 20 to permit longer slugs to be properly assembled by the pusher 18.

It will also be plain that I can quickly and readily lengthen or shorten the guide 65 20 to properly guide any length of slug which can be produced upon the machine, and that when producing full length slugs the guide can readily be folded back out of the way of the slugs as they are pushed 70 along the assembly platform 13.

As many modifications of my invention will readily suggest themselves to one skilled in the art, it should be understood that the scope of the claims is not limited to 75 the specific structures herein shown and described.

I claim:

1. In a linotype machine capable of producing type bars of various lengths and 80 having an inclined stick or slug assembly platform, the combination therewith of a laterally yieldable slug guide extending over said platform, said guide being retractable and extensible for accurately guiding type bars of various lengths as they slide down said inclined assembly platform.

2. In a linotype machine capable of producing type bars of various lengths and having an inclined stick or slug assembly 90 platform down which the slugs are adapted to slide to be assembled in column form, a slug assembly member adapted to push the slugs laterally into column form, and a foldable guide arranged over said stick 95 adapted to be pulled out or pushed back to adjust its length to correspond with the length of the slugs being produced, and said guide being yieldable in the direction of the transverse movement of the slugs as they 100 are assembled into column form to prevent inadvertent stoppage of the slug assembler.

3. In a machine of the kind described, having an inclined assembly platform down which the type bars slide to be assembled in column form, a guide projecting over the platform composed of a plurality of yieldable members pivotally joined at their ends and adapted to be extended over the platform in end to end relation to guide short 110 length type bars down the platform and adapted to be folded back in parallel relation to properly guide longer type bars down the assembly platform and to permit the longer type bars to be moved transversely by the assembler member.

In testimony whereof, I have hereunto set my hand this 2 day of February, A. D. 1918.

CHARLES L. MOHR.
